UNITED STATES PATENT OFFICE.

WILLIAM GORMAN, OF NEW BRITAIN, CONNECTICUT, ASSIGNOR TO THE RUSSELL & ERWIN MANUFACTURING COMPANY, OF SAME PLACE.

DESIGN FOR DOOR-KNOB AND ROSE.

Specification forming part of Design No. 7,093, dated January 6, 1874; application filed September 22, 1873.
[Term of Patent 14 years.]

To all whom it may concern:

Be it known that I, WILLIAM GORMAN, of New Britain, in the county of Hartford and State of Connecticut, have invented a new and useful Design for a Door-Knob and the Rose belonging to the same; and I do hereby declare that the following specification, taken in connection with the drawings, is a description thereof.

Figures 1 and 2 are views, respectively, of the design for the obverse and the reverse of the knob. Fig. 3 represents the design for the rose.

The design for the obverse of the knob is shown at Fig. 1 of the drawing.

A represents a rosette, which composes the central figure, and is inclosed within a circular band, the face of which may be spotted. The extreme edge of the obverse face is bounded by a band-line, *a*, and the annular space between it and the circular band before mentioned is ornamented with an endless band, *b*, arranged to form a series of Gothic points, the spaces within the points and the outer spaces formed by the intersection of the points being occupied, respectively, with large and small trefoils.

The characteristic feature of this design is the effect which is produced by the grouping

of the several members above mentioned, substantially as shown.

The design for the reverse of the knob is shown at Fig. 2, and is composed of a central rosette, *B*, with pointed leaves of Gothic design, surrounded by a matted ground, relieved by the leaf-work shown.

The design for the knob-rose is exhibited at Fig. 3, and is composed of the scroll-work *c*, in relief, upon a matted ground, giving, in contrast with the ground, the effect shown.

Fig. 4 represents the general contour of the knob and its rose-plate in side view.

What I claim as new, and desire to secure by Letters Patent, is—

1. The design for the obverse of a knob, substantially as described, and shown at Fig. 1 of the drawing.

2. The design for the reverse of a knob, substantially as described, and shown at Fig. 2 of the drawing.

3. The design for the knob-rose, substantially as described, and shown at Fig. 3 of the drawing.

WILLIAM GORMAN.
